CLAIM

The ornamental design for a watch, as shown and described.

DESCRIPTION

FIG. 1 is a perspective view of a watch showing my new design, in a closed position;

FIG. 2 is a front view of the watch shown in FIG. 1;

FIG. 3 is a rear view of the watch shown in FIG. 1;

FIG. 4 is a left side view of the watch shown in FIG. 1;

FIG. 5 is a right side view of the watch shown in FIG. 1;

FIG. 6 is a top view of the watch shown in FIG. 1; and,

FIG. 7 is a bottom view of the watch shown in FIG. 1.

The broken lines showing movable items in FIGS. 1 and 6 are for illustrative purposes only and form no part of the claimed design.
